HANDLING ROLLED MATERIAL

Josef Gassen, Dusseldorf, Germany, assignor to
 Schloemann Aktiengesellschaft, Dusseldorf,
 Germany, a German corporation

Application August 21, 1935, Serial No. 37,123
 In Germany June 14, 1934

3 Claims (Cl. 198—219)

My invention relates to the handling of rolled material and particularly to the conveying of rolled rods of steel to their bundling places or stations from the cold shears which cut the rods into commercial lengths.

This bundling is usually carried out by manual labour in that a certain number of rods is segregated by means of hooks or like implements out from the bulk of rods on the delivery conveyor of the cold shears and then is tied fast into bundles or packs. The cold shears are generally operated so that they cut simultaneously very large numbers of rods in rapid succession which requires a correspondingly large number of bundles to be made up quickly to keep up with the output of such mills. The rods when delivered from the cold shears to the bundling places are piled up in heaps so that the rods become very much entangled or matted with another. In the operation of unravelling the rods and counting an exact number of them into the hooks it frequently occurs that the finished bundles either contain to many or too few rods, which is of course objectionable. It also happens that the operation of the shears must be stopped altogether for some time. These drawbacks are still further increased by the fact, that there is very often not space enough for sufficient bundling places to deal with the output of the mill to be arranged.

It is an object of my invention to facilitate the handling of larger outputs of rod mills at the bundling places than is now possible and at the same time to insure that each bundle is made up of the correct number of rods.

It is a further object of my invention to provide an improved apparatus which permits of arranging a sufficient number of bundling places to deal with the output of modern rod mills.

It is a further object of my invention to provide for bundles of different sizes to be handled at one time.

An apparatus embodying my invention comprises a shaking device by means of which the rods coming from the cold shears are spread out spaced apart in a single layer prior to their bundling. Thus, each individual rod is freed from entanglement with the adjacent rods and can be readily grasped by hooks.

In the accompanying drawing, in which I have shown one embodiment of my invention by way of example,

Fig. 1 is a part of the layout of a steel mill plant, incorporating my invention;

Fig. 2 is a section along line II—II in Fig. 1, on a greatly enlarged scale.

In Fig. 1, 10 designates a cold shear to which rolled steel rods are fed in groups in the direction of the arrow 11 from a cooling bed not shown. 5 From the cold shear 10, the rods are delivered to a roller table 12 to which is fitted a stopper member also not shown for adjusting the length of cut. Further stopper members are arranged on the roller table 12 to limit the distance by which 10 the individual groups of rods are fed forward after each cutting operation. All these parts are of well known design and therefore need not to be further described.

Beside the roller table 12 is provided a shaking device which comprises two groups of parallel bars 13 and 13' which with their ends adjacent the roller table 12 are supported upon eccentrics 14 and 14' respectively (Fig. 2) mounted on a common shaft 15, the said bars 13, 13' having straps or their equivalents cooperating with said eccentrics 14, 14' as shown in Fig. 2, so that rotation of said eccentrics results in said bars being oscillated vertically and, at the same time, reciprocated. The other ends of the bars are freely supported on rollers 16 mounted on a frame 17. As will be readily apparent from Fig. 2, the eccentrics 14 and 14' which act upon the two groups of bars 13 and 13' are offset with respect to each other so that one group of bars is always in its raised position while the other group is lowered. For transferring the rods from the roller table 12 to the shaking device, rocking members 18 are swingingly mounted on a shaft 19, by means of which members the rods are pushed off from the roller table to an inclined surface 20 at the lower end of which vertically movable stops 21 are provided.

At the forward ends of the bars 13 and 13', the first bundling places are located which are generally designated in Fig. 1 by the reference letter A. The bundling places are equipped with trough-like receptacles, formed by curved arms 22 (Fig. 2) which are rockingly mounted at 23 on the frame of the shaking device and are held in their raised position by means of fingers 24 rotatable about an axis 25 and counterbalanced at 26. The fingers 24 are controlled by means of pedals 27 provided at the bottom of the bundling places A, the connection between the pedals 27 and the fingers 24 being effected by any suitable means not shown.

Below the curved arms 22 and in front of the bundling places A is provided a second roller table 28 which extends beyond the shaking de-

vice to other bundling places which are generally designated in Fig. 1 by the reference letter B. The rollers of table 28 are provided with grooves as shown in Fig. 2 which form a plurality of 5 channels 29 lying side by side. In order to direct the material to the different channels, guideways are provided intermediate the curved arms 22 and the roller table 28, which guideways have side walls 30 and 31. The inclination of the side 10 walls 30 and 31 is adjustable by means of a pin-and hole-connection of their respective angular extensions 32 and 33 with their supporting brackets.

In operation, the rods are fed to the cold shear 15 10 in groups up to 150, are cut into commercial lengths and then are delivered to the roller table 12. By means of the different stopper members on that roller table, the successive groups are moved step by step along the roller table, until 20 the whole length of the latter is taken up by the groups. The various groups of rods are then transferred by means of the rocking members 18 to the inclined surface 20 at the bottom end of which they are arrested by the stops 21 thus 25 being piled up in heaps. After the withdrawal of the stops 21, the rods pass on to the bars 13 and 13' of the shaking device.

The rods arriving at the shaking device are piled up without any definite order in a tangled 30 state and matted more or less together. By the continuous alternate up- and down-movement, however, of the bars 13 and 13', the rods are separated from each other spreading out in a single layer in spaced apart relationship so that 35 they can be easily grasped one by one by hooks. The up- and down-movement of the bars 13 and 13' at the same time causes the rods to be gradually advanced from end to end while they are being separated.

40 The rods are caught by the hooks in the desired number and then are deposited into the curved arms 22 at the bundling places A, where they are tied fast by wire or other means to form small bundles. Thereupon the arms 22 are 45 swung downwards so that the bundles drop down the guideway defined by the inclined side walls 30 and 31 and into one of the channels 29 of the roller table 28.

It is to be understood that other embodiments 50 than that shown and described here are within the scope of my invention. Thus it is possible in order to deal with still larger outputs, to du-

plicate the whole system by arranging a second shaking device together with bundling places A and B at the other side of the roller table 12 whereas for smaller outputs the bundling places may be arranged only at one side of the roller 5 table 28. It is also within the scope of my invention, to use a different type of shaking device than that shown and described.

I claim as my invention:

1. In an apparatus for bundling cut rolled rods, 10 and the like, the combination with a roller table adapted to receive the cut rods, of a shaking device, a means for successively transferring the rolled rods in separated groups from said roller table to said shaking device, and means for 15 operating said shaking device so as to impart to the groups of rods a simultaneous oscillating and reciprocating motion, to cause the rods to assume a single layer, parallel relationship to each other on said shaking device and to be advanced gradually across said shaking device to a bundling station, said shaking device being constructed and arranged to operate to advance the rods across the same at progressively decreasing velocity, 20 whereby the rods are caused to collect with respect to each other as they approach the bundling station. 25

2. In an apparatus for bundling cut rolled rods, 30 and the like, the combination with a roller table adapted to receive the cut rods, of a means for piling up the cut rods in groups, a shaking device adapted to successively receive the groups of rods and comprising two pairs of elongated bars extending in parallel relationship from said roller table toward the bundling station, means freely 35 supporting said pairs of bars at their discharge ends, and means adjacent to the rod receiving ends of said bars for imparting to each pair of bars a simultaneous oscillating and reciprocating motion with the movements of one pair of bars 40 alternating with the movements of the other pair, thereby separating to cause the bars to initially assume a single layer, parallel relationship on said bars and to be advanced along said bars to the bundling station at progressively decreasing velocity so as to collect with respect to each other as they approach the bundling station. 45

3. The combination as specified in claim 2, including a means for successively releasing the piled up groups of cut rods to be received by said 50 shaking device.

JOSEF GASSEN.
